PLATE SHAVING MACHINE

William J. Lofstedt, Portland, Oreg., assignor, by
mesne assignments, of two-thirds to Premier
Manufacturing and Sales Company, Portland,
Oreg., and one-third to Ralph H. Mort

Application March 7, 1936, Serial No. 67,687

2 Claims. (Cl. 90—18)

This invention relates generally to the printers' art and particularly to plate shaving machines.

The main object of this invention is the provision of an improved form of plate shaving machine possessing certain advantages over the machine described in my copending application, Ser. No. 742,378, filed Sept. 1, 1934, Patent #2,064,172, Dec. 15, 1936, among which is the provision of a pneumatic chip remover, means for segregating various kinds of chips, and a generally improved construction over that illustrated in the patent application referred to.

I accomplish this and other objects in the manner set forth in the following specification as illustrated in the accompanying drawings, in which:

Fig. 1 is a perspective view of the complete machine with part of the chip hopper broken away.

Fig. 2 is a section taken along the line 2—2 in Fig. 5.

Fig. 3 is a perspective view showing the reversing mechanism.

Fig. 4 is a fragmentary plan showing one end of the spiral cutter, the bed plate, and the side and end stops.

Fig. 5 is a section taken along the line 5—5 in Fig. 1.

Fig. 6 is a section taken along the line 6—6 in Fig. 5.

Fig. 7 is a plan of the indicating dial.

Fig. 8 is a fragmentary section through a portion of the oiling roll.

Fig. 9 is a fragmentary section of the chip outlet duct showing a modification wherein two separate chip collectors are provided for wood and metal chips.

Fig. 10 is a section through the trip arm.

Similar numbers of reference refer to similar parts throughout the several views.

Referring in detail to the drawings, there is shown a frame 10 across the top of which is formed a dovetail guide 11 upon which is mounted a slide 12. To the slide 12 is secured a nut 13 through which extends a feed screw 14 whose ends journal in the frame 10. On the screw 14 is secured a gear 15 which meshes with the gear 16 on the shaft 17 which journals in the frame 10 and has secured on one end thereof a bevel gear 18 which meshes with a second bevel gear 19 on the reversing clutch shaft 20 which journals in the frame 10.

On the shaft 20 are rotatably mounted the gears 21 and 22, the former meshing with an idler

pinion 23 which in turn meshes with a gear 24 secured to the shaft 25. The gear 22 meshes directly with the gear 26 secured on the shaft 25. Splined on the shaft 20 between the gears 21 and 22 is a slideable clutch jaw, 27, the teeth of which are adapted to engage the jaw 28 on the gear 21 or the jaw 29 on the gear 22. The slideable jaw 27 is actuated by means of a fork 30 on the rock shaft 31 which is operated through the bevel gears 32 from the rock shaft 33.

The shaft 33 is provided at one end with a hand lever 34 and at the other end with an arm 35.

Mounted within the frame 10 is a horizontal shaft 36 which supports one side of a motor base 37 whose opposite side is supported by means of a rod 38 which in turn is suspended from the spring 39 which is carried by the side frame 10. Upon the base 37 rests a motor 40 around whose sheave 41 pass the belts 42 which pass around the multiple sheave 43 on the shaft 44 of the spirally fluted cutter 45 which journals in the standards 46 which in turn are supported by the frame 10.

The slide 12 is provided with a rectangular opening 47 along one end of which is mounted an end stop 48 and along one side of which is mounted a side stop 49.

It is desirable to provide a cleaning space 50 at the junction of the end stop 48 and the side stop 49.

On the shaft 44 is also a grooved pulley 51 whose belt 52 passes around a grooved pulley 53 whose shaft 54 is mounted on a slotted quadrant arm 55 which is rockable on the shaft 25. To the pulley 53 is secured a spur gear 56 which meshes with a gear 57 secured on the shaft 25. The pulley 53 is mounted on the quadrant arm 55 merely for the purpose of providing a convenient tightener for the belt 52. Within the opening 47 is disposed a vertically slideable bed 58 which is free to move in the corner formed by the stops 48 and 49. The bed 58 is provided with a pillar 59 which is slideable within the slide 12. On the under side of the bed 58 is formed the inclined edge 60 which rests upon the inclined edge 61 of the slideable wedge 62 to which is secured a nut 63 through which passes the screw 64 which is manually operated by means of a hand wheel 65.

A graduated dial 66 is provided on the screw 64 for fractional readings and a worm 67 on the screw 64 meshes with a worm wheel 68 on the stud bolt 69. Integral with the worm wheel 68 is a pinion 70, which meshes with a gear 71 which in turn drives a sleeve 72. Frictionally mounted

in the sleeve 72 is an indicating dial shaft 73 on whose upper end is secured a hand or pointer 74 which lies above a dial 75 which is protected by a glass cover 76. The position of the pointer 74 with relation to the setting of the screw 64 can be adjusted at will by means of the knurled head 77.

Between the standards 46 is mounted a cutter housing 78 which is provided with an inspection opening 79 over which is placed a closure 80. The housing 78 is provided with an inclined side 81 along the lower edge of which is placed a chip deflector 82 which consists of a plurality of spring urged fingers which extend under the discharge side 81 of the cutter 45 and are urged downwardly upon the plate 83 by means of the springs 84. At the upper edge of the inclined side 81 is a chip outlet opening 85 which is connected by means of a manifold 86 to the intake side 87 of the blower fan 88. The manifold 86 has its side 89 sloping to facilitate the movement of the chips from the cutter 45 into the fan casing 90 from which they are discharged through the duct 91 into the head 92 which is removably placed over the wheeled can 93 into which the chips 94 are deposited. The head 92 is provided with a central opening 95 from which the air can escape. In some cases, for example, when wood and metal plates are to be shaved alternately, it is desirable to provide an additional can 96 and to separate the pipe 91 into two outlets 97 and 98 and to control the flow of air to either of the outlets by means of a damper 99 which is controlled by a hand lever 100. The fan 88 is provided with a drive pulley 101 whose belt 102 is driven from the sheave 103 on the shaft 44.

Journaling under the manifold 86 is a trunnion 104 on one end of which is secured a lever 105 which is joined by a connecting rod 106 to the arm 35. On the trunnion 104 is secured a trip arm 107 which is of a sufficient length to clear the top edge 108 of the end and side stops 48 and 49 plus the thickness of the maximum cut intended to be taken. Hingedly attached to the trunnion 104 are the arms 109 to which is attached the oiling roller 110 which is preferably of felt mounted on a perforated sleeve 111.

On the shaft 33 is secured a bevel gear 112 which meshes with a bevel gear 113 on the shaft 114 to which is secured a segment gear 115 which meshes with a rack 116 on the vertical plunger 117 on whose upper end is secured a head 118 whose upper and lower sides 119 and 120 are beveled to facilitate their engagement with the trip locks 121 and 122 which are secured on the slide 12.

A cutting lubricant such as kerosene is stored in the cup 123 which communicates by means of the pipe 124 with the sleeve 111. It is desirable to permit the pipe 124 to slide vertically with relation to the manifold 86 in order that the roller 110 may move.

The operation of the device is as follows:

A plate 83 is placed on the bed 58 against the stops 48 and 49. The motor 40 is then operated through the closing of a switch, not shown, causing the cutter 45 to rotate rapidly and also causing the shaft 25 to rotate, thereby revolving the gears 21 and 22 in opposite directions, also permitting the shaft 20 to remain idle by reason of the fact that the jaw 27 is in a neutral position. A movement of the hand lever 34 in one direction will cause the jaw 27 to engage the jaw 28 and thereby impart rotation to the feed screw 14, causing the slide 12 to move along the guide

11 and move the plate 83 under the trip arm 107 and under the roller 110 as well as under the chip deflector 82 after which the plate 83 comes into engagement with the spiral cutter 45. The plate is then shaved to a thickness determined by the setting of the hand wheel 65.

It will be noted that the action of the spiral cutter 45 is such that it holds the plate 83 firmly against the bed 58 as well as against the stops 48 and 49, thereby rendering unnecessary the use of any special clamps for holding purposes.

When the slide 12 has moved to a distance at which the trip block 122 will engage the side 120 of the head 118, it will cause the rack 116 to rise and automatically move the lever 34 to a neutral position from which the lever 34 can be moved only toward a reversing position by a manual operation thereof. This will cause the slide 12 to return to its starting point at which time the trip block 121 will engage the upper side 119 of the head 118, thereby returning the jaw 27 to a neutral position.

If the plate 83 is thick enough to engage the trip arm 107, that is, when an attempt is made to take an excessively deep cut, this will cause the connecting rod 106 to rise, also moving the jaw 27 to a neutral position.

In some cases, it will be found desirable to provide a vibration absorbing roller 125 adjacent to the cutter 45 on the side opposite the roller 110.

It will be understood that none of the members 107, 110, 82, or 125 serve to hold the plate down upon the bed 58. This action is accomplished entirely by the cutter 45 itself. It will be noted that the chips 94 which are removed by the cutter 45 are deflected upwardly by the members 82, the action of the cutter 45 being such as to cause them to move obliquely toward the fan 88 and thereby be discharged into the container 93. Or, if the arrangement shown in Fig. 9 is employed, the chips 94 may be deflected into either of the cans 93 and 96 by the operation of the hand lever 100.

Referring to Fig. 10, it will be seen that the trip arm 107 is slidable within the bar 126 and the arm 107 is urged downwardly by means of springs 127 on the bolts 128 which are slidable within the bar 126. The bolts 127 are provided with the nuts 129 for adjusting purposes.

It is desirable to bevel the face 130 of the trip arm 107 as shown. The bar 126 is provided with the trunnions 104 which also form centers for the arms 109 of the oiling roller 110. The purpose in making the trip arm 107 yieldable is to prevent it from biting into the plate 83 when it is withdrawn.

While the roller 110 has been referred to as an oiling roller, it also serves as a holdown roller for the rear end of the plate to prevent it from tipping up when its forward edge engages the chip deflectors 82 and its dual purpose must be so understood.

I claim:

1. A plate shaving machine having in combination a vertically adjustable horizontally movable bed plate, a driving means for slidably moving said bed plate, side and end stops associated with said bed plate, a spiral cutter mounted over said bed plate, chip deflectors disposed along said cutter, an oiling roller disposed in advance of said chip deflectors and a trip arm disposed over said bed plate together with a clutch interposed between the drive mechanism and a source of power actuated by said trip arm whereby a plate

of excessive thickness will cause said drive mechanism to move to a neutral position.

2. A plate shaving machine having in combination a frame, a horizontal guide disposed on said frame, a slide mounted on said guide including means for driving same in either direction, a clutch interposed in said drive means, a bed plate vertically adjustable within said slide and projecting through the top thereof, side and end stops for said bed plate mounted on said slide, a spiral cutter mounted over said bed plate, a

vibration absorbing roller on one side of said cutter and a chip deflector on the opposite side thereof, a chip collecting manifold associated with said chip deflector, an exhaust fan having its inlet communicating with said manifold and a trip arm disposed under said manifold including operating connections to said clutch whereby the passage of a plate of excessive thickness under said trip arm will cause said arm to move said clutch to a neutral position.

WILLIAM J. LOFSTEDT.
